COMMUTATOR ASSEMBLING MACHINE

Elmo H. Kroener, Franklin, Ohio, assignor, by
mesne assignments, to The Third National
Bank and Trust Company of Dayton, Dayton,
Ohio

Application May 7, 1945, Serial No. 592,467

13 Claims. (Cl. 29—203)

1

In application for Letters Patent Serial No. 534,498 filed May 6, 1944, now Patent No. 2,394,955, granted February 12, 1946, by Walter C. Weber is described a machine for assembling commutator bars or segments with interlying mica strips, using a ring shaped form within a holder which is removable, and which is arranged to grip the assembly and hold it together during the insertion into the segment assembly of a sleeve and retaining collars, and the upsetting thereof to retain the ring shaped structure in permanent position. In this machine the segments are fed flatwise, one at a time, to the space within the removable holder, and are held by a pair of rubber faced revolving members or heads which come into engagement with the ends of the segments as they are inserted. Also in this machine there is provided in connection with one of the heads, a small platform or finger which projects into the space between the heads and within the removable tool, so as to provide a radially extending support for the first of the segments to be thrust between the rotating rubber faced heads. Thereafter the previous segment supports the next one until the final segment is thrust into place, whereupon the cycle of the machine as arranged comes to an end, the rotating heads and the small platform are withdrawn and a portion of the tool is manipulated to clamp the assembly tightly, whereupon the tool is withdrawn for assembling with the sleeve and collars.

The present invention has as its primary object, the replacing of hand work in connection with the various operations required in the former machine. As one item, the operations are controlled by hydraulic power, the controls being in the form of valves, a control drum sequence mechanism being provided with stops or abutments which can be set to supply various elements with fluid in accordance with the timed cycle of the apparatus. The operations are performed by means of pistons which may have either spring or hydraulic returns.

Commutators of various sizes and with various numbers of bars per commutator present a wide variety of conditions, requiring adjustments for fully automatic operation, and the indexing of the parts, and inter-action of the several mechanisms if done automatically must be done positively and in proper sequence. Thus it has been necessary to develop various hydraulic and mechanical devices which will accomplish the various movements. There have also been improvements in the several devices of the Weber machine above referred to.

2

In the drawings and the specification that follow, there is illustrated and described the embodiment of the invention which has been placed in operation; and by describing it in full, it is not intended to exclude modifications in the structures described, so long as they fall within the inventive concepts inherent in the described structure, as to which reference is hereby made to the appended claims.

10 In the drawings:

Figure 1 is a fragmentary plan view of my invention.

Figure 2 is a front elevation of the machine with parts broken away and other parts in section.

15 Figure 3 is a rear elevational view with parts broken away.

Figure 4 is a sectional view taken on the line 4—4 of Figure 3.

20 Figure 5 is an enlarged sectional view taken on line 5—5 of Figure 2.

Figure 6 is a sectional view of the receiving tool taken on line 6—6 of Figure 7.

25 Figure 7 is a view taken on the line 7—7 of Figure 6.

Figure 8 is a front elevation of one of the valve members.

Figure 9 is a section taken on the line 9—9 of Figure 8.

30 Figure 10 is a front elevation of another valve.

Figure 11 is a section taken on the line 11—11 of Figure 10.

Figure 12 is an enlarged view of the work heads with parts broken away and parts in section.

35 Figure 13 is a section on line 13—13 of Figure 1.

Figure 14 is an hydraulic control system of the machine.

Referring generally to Figures 1, 2, 3 and 4, the frame work of the machine is shown at 1, the 40 valve chest or hydraulic manifold at 2, the valve operating drum at 3. What may be termed the work table is shown at 4, this being secured in a space left for it in the main framework, and having an apron 4a secured to the frame. The slotted structure for holding the gravity feed stack of mica strips is shown at 5. The two rubber faced heads which grasp the ends of the segments as they thrust from machine by the segment feed (and which index around to receive additional segments) are shown at 6, and 6a, in Figures 2 and 3 and the receiving tool is generally indicated at 7, held in adjusted relation on the work table, as will be described.

An initial drive motor is shown at 8 in Figure 45 14, and is combined with an hydraulic pump 9. A fluid motor 9a, is provided to rotate the drum

3, and all of the other parts of the machine are operated by hydraulic power.

The receiving tool (Figs. 6 and 7)

In its general structure and mode of operation the receiving tool 7 is alike to that shown and described in the Weber patent above noted. There are three standards, see especially Figure 7, on the table 4—the standard 10, which has a slotted pad 11 on the top thereof, and an upwardly projecting post 12 carrying an adjustable abutment pin 13—the standard 17, which is divided into ears which support a pivot pin 15 for a bell crank 16—and the standard 18, which is equipped with an abutment plate 18, and is grooved as indicated at 19, see Figures 4 and 7, to receive a lip on the receiving tool which slides into the groove and engages that portion of the abutment plate 18, which bridges the groove.

The tool itself, of which the main frame portion is indicated at 7, is constructed to provide a bearing 20a for one end of a thrust rod 20. Pivoted in a horizontally extended slotted portion 19a of the frame adjacent this bearing is an operating bell crank lever 21, which has its short arm lying over the exposed end of the thrust rod 20. The other end of the lever is formed with a latching face as at 22. The bell crank 16 when it is rocked, as will be described, engages the lever 21 and pushes it toward the body of the frame 7 of the tool. The result is to push the thrust rod lengthwise of the tool frame, a latch 23 pivoted to the frame, and which is pressed by a spring pin 24, engages the latch face 22 and has two steps formed therein. The outer step simply holds the bell crank 21 when it is not pressing on the thrust rod, whereas the inner step (as shown in Figure 6), holds the bell crank when in its position of thrusting the rod forward. The frame of the tool also has a bearing 25 for the forward end of the push rod. At this point ears 26, four in number, project upwardly and downwardly from the end of the frame and serve to receive mounting screws 27. The mounting screws engage the end portions 28 of a steel part 29, which houses the assembly retaining ring.

The part 29, see Figure 6, has a central hole through it which accommodates an extension 30 of the thrust rod 20. The portion 30 is made smaller than the remainder of the thrust rod, as shown, and engages a resilient ring 31, see Figure 7, held within the part 29. The structure of the ring 31 is such that it is thicker at the middle, tapers toward its ends, and has its ends separated so that it is an incomplete annulus. The part 29 has a circular opening or jaw, which houses the ring 31. This jaw is likewise an incomplete ring, and it is through the opening in these two rings that commutator segments are thrust sidewise into assembly position.

The resilient ring tends to remain open to its greatest extent within the jaw formed by the steel part 29. By pressing on the thrust rod, the ring is forced outwardly in the jaw, thus constricting the ring due to the proportioning of the parts. Thus an annular assembly of segments can be set up in the ring, and then gripped by the ring by operating the bell crank 21, which pushes the thrust rod, which in turn forces the ring to constricting position.

The reason for making the jaw element detachable from the frame 7 is to accommodate different sized commutators. Due to the loca-

tion of the remainder of the assembling mechanism, the center of the jaw element must be close to the center of the indexing and holding devices. Hence a different jaw with a different length thrust rod will be used for different sized assemblies.

The lower part of the jaw has a stepped lip 32, which engages in the groove 19 and under the abutment plate 18. The inner end of the main casting of the tool has a pin 33 depending therefrom which slides in the slot in the pad 11. As so arranged when the tool is dropped into place, it is located in crosswise relation by the pin 33 in the slot in the pad 11, and in lengthwise position by the step 18, 19, and by the engagement of the abutment pin 13 with the bell crank 21.

An abutment screw 1a serves to oppose dislodgment when the bell crank 16 is operated (Figure 6).

It will be noted that the rear abutment stud 13 does not directly engage the thrust rod 20. An adjustable screw 21a in the pivoted arm of the bell crank 21 engages the end of the rod 20. The stud 13 engages the bell crank, thus permitting an adjustment of the clamping action of rod 20. The reason for this construction is that when the bell crank is rocked to push forward the rod 20, the rear portion of the bell crank moves to the right (Figs. 6 and 7), and as a result the whole tool can shift slightly to the left, leaving the center of the split ring 31 where it was originally. This shifting is caused by the engagement between the resilient ring and a demountable supporting block 41, supra. (See also Figure 4.) In effect what happens is that the tool shifts to the left while the split ring retains its original center. This permits the indexing heads to be retracted after the tool has been clamped.

Let us suppose that the receiving tool has been dropped into position as indicated and a commutator assembly has been set up within the resilient ring of the tool, with the bell crank 21 in its outer position. The machine is arranged at this juncture automatically, with the finishing of the assembly, to cause the tip 34 of a piston 35 to be pushed upwardly, with the result of clamping the work in place, with the bell crank 21 moving to its inner latched position under the influence of bell crank 16. The piston 35 is arranged in a cylinder casting 36 supported from the table portion 4, and is caused to move by oil under pressure from the passage 98, see Figure 14. A spring 16a, acting on the bell crank 16, will return the piston 35 to starting position.

Once the tool is thus clamped around the assembly, the tool can be lifted away, and transferred to a press which is indicated at 37, Fig. 14, and which may be hydraulically supplied from the assembling machine. This press is used to insert the sleeve and collars and upset them to complete the assembly for machining, if necessary, etc.

In Figure 7 has been indicated an adjustable abutment screw 38a, located in the standard 17, which may be used for adjusting the position of the standard in a groove of the table whereby the outer end of the tool when installing it in the machine for an assembling operation can be definitely located.

While the tool as described is bodily removable for further work on the assembly of commutator segments and insulation, it is evident that it

5

could be adapted for use with a turret which will automatically index a receiving tool in place, and trip the latch 23 to loosen its grip on the assembly after it has been moved through a staking position as by the press 37.

The segment ejector (Figure 4).

As already indicated, a supply of mica pieces for insulation between the commutator segments is placed in the holder 5 from which the mica pieces feed down by gravity. This is the same as in the former Weber machine, already referred to. Mounted and guided in a channel in the frame which is closed by the projecting frame work of the holder 5 is a main slide member 45a (Figure 4). This slide is connected by a key with a block 39 mounted on a rod 40, which is hydraulically operated, and of a detailed construction which will be described in connection with the indexing piston as shown in Figure 5. The slide member 45a rests on a member 38 fixed in the frame. The key connecting slide 45a with rod 40 extends through a slot 38a in the member 38. In Figure 4 a small diameter end portion 41 of the rod forms an internal piston and is subject to constant hydraulic pressure in a cylinder 43 at the left in the figure. The rod 40 also has a portion of the full diameter of the rod, subjected to intermittent hydraulic pressure in a cylinder 44 at the right in the figure through the port 42, which pressure can overcome, due to the larger area of the rod, the pressure on the internal piston portion 41, thus pushing the rod to the left. The rod is exposed between the cylinder 43 toward the rear of the frame and the cylinder 44 toward the front of the frame, and it is on the intervening portion that the block 39 is mounted.

Referring again to the slide 45a, it is equipped with an operating portion 45, pinned to it so as to slide in a shallower channel arranged to support this portion 45 on a line just below the center of the retaining tool jaw. The outer end of the portion 45, as indicated at 46, is special to the particular size of commutator segment which is being used on the job at hand. Hence the supplemental sliding member is changed with the job and merely drops over the stud on the main slide 45a. A demountable supporting block 47 underlies the advance end portion 46, to accommodate segments of different size and is also changed in changing the job in the machine along with the operating portion 45 and the receiving tool itself. The demountable block 47 is removably secured to the member 38.

In time with the indexing device to be described below, and operating when it comes to rest after each step of movement, oil under pressure is injected into the port 42. This causes the rod 40 to move to the left (Figure 4); and then with the release of hydraulic pressure the constant pressure on the internal piston element pushes the slide forward over the special shelf or block 47, and ejects a commutator segment which has been fed to position parallel with the table, along with the mica piece which rests upon it after descending from the holder 5. This step of the operation is the same as in the Weber machine of the patent noted above. The result is to thrust the pair of pieces into the open jaw of the receiving tool, and into the grip of the indexing heads, which themselves function as do the indexing devices or "sleeves" in the Weber machine.

6

The indexing and holding heads (Figure 12).

We have already referred to Figures 1, 2 and 3 which show the rubber faced heads 6, 6a, into the grip of which the segments and mica pieces are thrust, and which rotate around step by step following each insertion. The two members are shown, Figure 12, with the rubber facing rings 48. The machine will be provided with fingers (not shown but described in said Weber patent for depressing the rubber at the point of insertion of the segments). The heads are mounted on rotary and reciprocating plungers 49, 50, respectively.

15 The head 6a on the plunger 50 is provided with a T-shaped finger 51, which slides in a slot 52 with the head (see Figure 12). The axially projecting portion 53 of this finger carries a small platform plate 54 which is normally held by means of a spring 54a, in a position to lie directly within the zone occupied by the commutator segments when ejected by the pusher into the space between the two rubber facing rings 48.

20 At the start of an operation the head 6a is placed in a position such that the platform lies directly beneath the position onto which the first segment of an assembly is pushed, thus serving as a support for it. Thereafter as the head 6a revolves or indexes around step by step, the platform moves with it.

25 When the assembly is finished, the platform will naturally be included in it and must be withdrawn. At this point of time the retaining tool will not have been actuated to grip the assembly 30 tightly. But just as the timing of the machine arranges for the gripping of the retaining tool, an abutment plate 55 (Figs. 1, 12 and 13), held on the end of an hydraulic piston 56, will be caused to advance. The plate will strike the projecting end of the T-shaped finger 51, causing the finger to move, and the small platform to be moved into a position substantially on the axis of the assembly within the retaining tool. Thereupon the member 6a can be withdrawn, 35 which is accomplished hydraulically, as will now be described. The piston 56 is returned by a spring 56a (shown in Figure 13) at the start of the next commutator assembling operation.

The indexing mechanism operation

50 The object of the indexing mechanism is to rotate the members 6 and 6a around step by step and withdraw or push them to operative position in time with the other operations of the 55 machine. (See Figs. 2, 5 and 12.) The two heads 6 and 6a are mounted on the ends of shafts 49 and 50 which are axially aligned. The heads are replaceable for different commutator assemblies, and set screws 57 (Figure 12) engaging in flats 60 58 on the shafts will hold them demountably in place.

65 The two shafts enter the gear cases 57a and 58a (Figure 2) respectively and are there keyed and fitted to slide within sleeves 59, which have pinions 60 at their outer ends. A shaft 61 is mounted in the two gear cases and extends across between them, which shaft is rotated step by step. By means of pinions 62 and 63, the shaft engages the sleeve pinions and causes the two 70 shafts 49 and 50 to rotate in the same direction which in this case is counterclockwise, but without impeding the reciprocation of the shafts.

75 It is also necessary to move the shafts in and out within the sleeves which are held against sliding by means of their being provided with

thrust nuts 64 at their inner ends opposing the pinions 60 at their outer ends. The shafts are equipped with channeled rings 65 engaged each by a lug 66 mounted on a reciprocating piston rod 67, one for each shaft 49 and 50. The movement of the piston rods thus slides the shafts in and out of operating position.

The operation of the piston rods 67 which hold the lugs 66, is alike in both instances. There are two spaced cylinders 68 for each rod 67, with 10 ports 69a and 69b at opposite ends. The rods themselves are actuated simultaneously first by pressure applied at one end of each portion 67 in the cylinders 68, then by pressure applied at the other end of each piston 67 in the other 15 cylinders 68 of the same pairs.

For operating the indexing shaft 61 a device is supplied of the type already referred to for operating the segment pusher. A casting 70 (Fig. 5), embodying spaced cylinders is mounted within in the gear case. One of the cylinders has a port 71 therein and the other a port 71b therein. The pawl carrier 73 is mounted on the piston rod in between the cylinder portions 72. The piston rod 67a has a port 71a therein and is cored out to form a piston cylinder 74 into which cylinder, oil will flow through the port 71a. Within the cylinder 74 is a piston 75, which acts against an adjustable abutment plug 76 in the end of the main cylindrical casting. Oil from the port 71 as permitted by the annular groove 77 enters the inner cylinder and pushes the small piston 75, thus causing the main piston rod to move in the opposite direction. The port 71 is supplied with oil under constant pressure, and thus serves as a sort of hydraulic spring. The other end of the piston is acted on by hydraulic pressure entering the port 71b, and since the main piston rod is of much larger diameter than the smaller piston 75, the same pressure of oil will, when it flows through the port 71b, cause the main piston to overcome the effect of the small piston and move the main piston against the constant pressure on the small piston. As a result a momentary impulse of hydraulic pressure, immediately relaxed, through the port 71b, will cause a complete reciprocation of the main piston rod 67a, and move the pawl carrier to and fro, the length of movement being gauged by positioning the abutment 76.

Mounted on the shaft 61 is a ratchet pinion 78, held against motion in one direction by means of a ball 78b, and spring pin 78a, the ball riding in a cam groove in the bore of the pinion. The pawl 73a when it moves with the momentary impulse from the hydraulic control passes over the ratchet pinion and on the return stroke under the constant pressure impulse, moves the ratchet pinion one notch.

The shaft 61 extends out through the side of the left hand gear case, and is equipped with an operating knob 79 (Fig. 2). By this means the heads can be rotated by hand to bring the small platform on the head 6a to the proper position for the start of an operation on a given assembling job. Thereafter no initial indexing is required since a cycle requires that the platform be removed from the same position in a completed assembly that it occupied when a new assembly was started.

When shifting the numbers of strokes of the indexing operation for various numbers of commutator bars per assembly, the ratchet pinion 78 is changed so that for a given single movement of the ratchet pinion a different step of

movement is applied to the two heads 6 and 6a. Thus it takes a different number of ratchet movements to complete an assembly. Also the ratchet pawl carrier is adjustable for stroke by adjustment of the abutment 76. A simple way of demountably securing the ratchet pinion 78 is to equip the shaft 61 with a fixed collar 61a and hold the pinion in place thereon by means of screws 61b (Figures 2 and 5).

The hydraulic power and control devices

Referring first to the control diagram of Figure 14, the motor 8 is shown, and the hydraulic pump 9. The fluid motor 9a is shown which operates the rotating drum 3, not shown on this diagram. A speed control indicated at 80, which controls the speed of the drum 3, and a start valve 81 which supplies initial hydraulic power to the drum, are shown. This valve has a handle 81a (shown in Figures 1 and 2). As soon as the drum ceases to revolve, all parts of the machine stop having completed the cycle last above reviewed. There is an oil sump 82, and a pressure controlling and relief valve 83 in the line from the hydraulic pump.

The direct pressure from the relief valve flows through pipe 85 to a branch connection from which a pipe 86 enters the valve chest or hydraulic manifold 2, and pipes 87 and 88 extend to the segment pusher internal piston 41 (Figure 4), and the ratchet drive internal piston 75 through port 71 (Figure 5).

In the diagram of Figure 14 where there are two pipes emerging from the valve chest one above the other, the two pipes are controlled by one valve assembly, where there is but one pipe then the valve only operates from the valve chest in one direction. The pipe 89 extends to the full diameter end of the piston 40, and the pipe 90 extends to the full diameter end of the piston 67a, i. e., the port 71b. It will be noted that one valve assembly applies pressure intermittently to the pipes 89 and 90, thus obtaining interspaced operations of the idle operation of the pusher and the idle pawl and ratchet operation of the indexing drive shaft 61, which will be followed by the constant pressure position operation, of these two devices in interspaced timing.

The pipe 91 extends from the constant pressure in the valve chest to the starting valve from which pipe 91a extends to the speed control valve from which pipe 91b extends to the drum motor 9a whence pipe 91c extends to the sump. The pipe 92 extends from the valve chest to the starting valve, and normally supplies the hydraulic fluid through valve 81 to the drum motor. This control valve 81 may be of any type, such as are available on the market as two-way valves. When the pipe 92 is connected through the valve to pipe 91a, the pipe 91 is shut off. With the machine at rest, the valve drum motor may be started by operating valve 81 to supply fluid to the motor 9a through pipe 91 until the valve drum has opened the valve connected to pipe 92. Then if the valve 81 is thrown in the opposite direction the motor will continue to run with fluid supplied through pipe 92 until the valve on the valve chest automatically stops the motor by cutting off pipe 92.

The push toward operating position of the heads 6 and 6a is accomplished through pipe 95 having a branch 95a, and the push away from operating position of the two heads is accomplished through pipe 96, controlled through the other end of the same valve through branch 96c. The

abutment plate which moves the segment supporting platform, indicated in the diagram at 55, is put into operation through the pipe 97, and the piston 35 which clamps the retaining tool is operated through pipe 98. Pipes 97 and 98 are not coupled with a double acting valve. There is an exhaust passage from the valve chest to the oil sump through pipe 86a.

Referring now to the drum 3 (see Figure 3), it will be noted that it has a series of channels 3a therein, and in the channels may be located abutment pieces 3b which may be shifted from place to place, and secured by screws 3c in rows of holes 3d extending along the boundary walls of the channels. A toothed ring 99 is demountably secured at the one end of the drum and serves to operate the indexing piston and ratchet and the segment pusher. A simple way to make this member 99 demountable is to make it in two halves with screws 100 to enter the holes provided in the drum for that purpose. The drum rotates once for each operation from start to stop.

There are two types of valves used in the valve chest. To operate the valves a series of trip fingers 101 are pivoted on the valve chest casting, and extend rearwardly under the projecting ends of the spring plungers of the several valves. The fingers have a tapered tooth 102 on their under side which rides on the drum and is engaged by the adjusted abutment members 3b on the drum, there being one of these fingers that rides on the toothed ring 99, (Figure 9).

I will refer first to the valve device of the character used for the two members which are operated by the constant pressure applied to an internal piston, to-wit, the segment pusher and the piston for the indexing ratchet drive (Figs. 8 and 9). In the valve chest there is a passage 89a for connecting up to the pipe 89 to the pusher, and a passage 90a (Figure 9) leading to the pipe 90 for the ratchet drive. There is also an exhaust passage extending the full length of the chest as indicated at 103 and a full pressure passage extending the length of the chest indicated at 104.

Mounted on the face of the chest to register with the several passages now noted, is a valve casing 105, which has an exhaust passage 106, and exhaust ports 107 and 108 entering this exhaust passage, which connects up with the exhaust passage in the chest, and thence to the oil sump. Adjustment of the operation of the valves is through screw plugs 106a which enter the exhaust ports 107 and 108. The valve piston projects from the casing at 109. An opposite end portion controls the exhaust through port 107. There is also a full cylindrical portion 110 which controls alternately the two ports 110a and 110b which communicate with the full pressure passage 104. There are ports 89b and 90b connecting with the two passages 89a and 90a respectively, these ports extending into the piston chamber 111. A spring 112 keeps the valve piston in engagement with the trip finger 101. The full cylindrical portion 110 alternately sends pressure through the passages 89b and 90b. Another full cylindrical portion connects port 90b to the exhaust when the piston moves to shut off the positive pressure from said port.

Thus when the piston of this valve is pushed in by the trip finger, the segment feed is caused to operate, and when the piston returns under spring pressure the index ratchet is operated.

Referring to the other valves (see Figures 10

and 11), it has already been noted that all are of the same construction and where there is no double action involved, one side of the valve is simply plugged. The parts which are the same in these other valves are marked with like numbers to those of the valve and casing already described. The difference lies in the piston, and ducts which control pressure admission to the two outlet ports to the devices to be operated.

10 Thus the full pressure passage 104 in the valve chest has a single port 113 which is extended in the valve casing into the piston cylinder thereof, and two short full cylindrical portions 114 and 115, admit this pressure alternately to the two outlet ports which as an illustration are ports 95b and 96b leading to the chest ports 95c and 96c. This valve structure will operate the two pistons 67 of the index head reciprocating devices, first in one direction and then in the other.

15 Thus in Figure 11, when the valve piston is in the position shown, exhaust is connected to pipe 96 through port 96b and pressure is admitted to pipe 95 through port 95b, the piston rods 67 are then pushed inwardly to their regular position of operation. When the valve is pushed up by the trip finger, however, the pressure is cut off from the port 95c which is then connected with the exhaust and the pressure passes through port 95b and 96c, thus withdrawing the 20 heads from operation. Since the machine stops at this instant, and the drum pauses with the two heads withdrawn, it requires a starting up of the mechanism in order to cause the valve piston to drop and the two heads to move in 25 again. Pipes 97, 98 and 92 are supplied with pressure or connected with exhaust by using but one of the outlet ports of the valves of the type now described. In such a case a plug is inserted into the passages which are marked 30 95b or 96b in Figure 11.

35 A valve of the type last described is not so quick acting as the first described type. One of the second type is used to stop the drum motor, as already noted, through pipe 92; and since 40 the drum stops with the valve rod 109 elevated, as soon as the drum starts out through the operation of the valve 81 the piston 109 of the drum controlled valve will fall, and take over the oil supply to the drum motor.

45 To start the machine into operation after it has been stopped, due to the stopping of the drum, requires a manual operation. This will be accomplished by means of the hand lever 81a as already described. At once the drum starts 50 to revolve. Those devices which were operated at the conclusion of its operation such as the withdrawing plungers for the two heads 6 and 6a which were the last things to move, will come into operation. The location of the stops on the 55 drum control the relative timing of the various devices described.

60 By a change of ratchet for the indexing drive shaft, and substituting a new toothed member 99 on the control drum, a different number of rotating steps for the two indexing and retaining heads is provided for. By changing the supporting shelf for the segments, different sized segments are provided for, this requiring also a changing of the upper pusher member. By 65 changing the retaining tool jaw member, different sizes of assembly are provided for. By changing heads on the rotating and reciprocating plungers different diameter assemblies are provided for. By shifting the timing lugs on the 70 drum the point of operation of the several valves 75

is adjusted to proper relative timing. Insofar as concerns the segment feed and the indexing rotation of the two heads, this is positively prevented from getting out of time because the same valve plunger operates both members. In the machine as indicated in the diagram, it requires a hand operation to operate the staking press, but this could be coupled up with the valve chest and drum, if there were a turret operation for the retaining tool, this turret operation also being controlled from the drum and valve chest.

Since the operation of the several mechanisms has been detailed during the description, no further description of operation of the complete machine will be set forth; save to state that in the structure shown the retaining tool will first be installed, after the machine has been set up for a given operation, the heads indexed around to bring the supporting platform to the proper position, by hand operation, and the starting lever then swung over to release the drum for operation.

Having thus described my invention, what I claim as new and desire to secure by Letters Patent is:

1. In a commutator assembly machine: a work holder comprising a pair of opposed heads having compressible material on their opposed faces between which material segments may be inserted, shafts on which the heads are mounted, means for controlling the shafts comprising a sleeve surrounding each shaft and connected thereto so as to rotatably drive the shaft but allow for sliding movement of the shaft in the sleeve, step by step driving gearing connected to the sleeves for rotating the same and the heads, a reciprocable means for each shaft and connected thereto to slide the same within the sleeves for moving the heads together or apart, and power means for moving said reciprocable means; a work retaining means comprising a frame, a thrust rod in said frame, a housing detachably mounted in one end of said frame, an extension on said rod, said housing having a bearing for said rod extension, a split resilient ring maintained within a jaw provided in said housing, said rod extension engaging said ring, rearward and forward abutments located in said machine and between which abutments said frame and housing are mounted so as to position said jaw and said retaining ring between said opposed heads in position to surround the segments inserted between said opposed faces, a lever pivotally mounted on said frame and arranged when rocked to push said thrust rod lengthwise and thereby cause said ring to be constricted by said jaw about said segments, and power means for rocking said lever; and common control means for both of said power means whereby said shafts are reciprocated, and said thrust rod is actuated, in timed relation to one another.

2. The machine of claim 1 including power means connected to said gearing for effecting rotation of both sleeves simultaneously, said last mentioned power means also having an operative connection to said common control means.

3. The machine of claim 2 in which said common control means includes mechanism for altering relative movement of said various power means.

4. The machine of claim 2 in which said common control means has mechanism to stop all of said various power means after a cycle of operation and at a time when said reciprocable means have been moved to bring the shafts apart from

each other and said lever has been rocked to effect constriction of said ring about the segments inserted between the opposed faces of said heads.

5. A work holder comprising a pair of opposed heads having compressible material on their opposed faces between which material segments may be inserted, shafts on which the heads are mounted, means for controlling the shafts comprising a sleeve surrounding each shaft and connected thereto so as to rotatably drive the shaft but allow for sliding movement of the shaft in the sleeve, step by step driving gearing connected to the sleeves for rotating the same and the heads, a reciprocable means for each shaft and connected thereto to slide the same within the sleeves for moving the heads together or apart, and power means for moving said reciprocable means.

6. The combination of claim 5 including power means connected to said gearing for effecting movement of both sleeves simultaneously, and common control means for both of said power means.

7. The combination of claim 6 in which said common control means includes mechanism for altering relative movement of said power means.

8. The combination of claim 6 in which said common control means has mechanism to stop said power means after a cycle of operation and at a time when said reciprocable means have been moved to bring the shafts apart from each other.

9. A work holder comprising a pair of opposed heads having compressible material on their opposed faces between which material segments may be inserted, shafts on which the heads are mounted, means for controlling the shafts comprising a sleeve surrounding each shaft and connected thereto so as to rotatably drive the shaft but allow for sliding movement of the shaft in the sleeve, step by step driving gearing connected to the sleeves for rotating the same and the heads, a reciprocable means for each shaft and connected thereto to slide the same within the sleeves for moving the heads together or apart, and power means for moving said reciprocable means, one of said heads being provided with a supporting platform located between said opposed faces, means mounting said platform for movement diametrically of said head, means normally holding said platform in one extreme of movement adjacent the periphery of said heads, power means for moving said platform from its normal position to a position axially with respect to said opposed faces, and common control means for both of said power means.

10. The work holder of claim 9 in which said platform is fixed to one end of an arm of a T-shaped member, a slot in said one head, the other arm of said T-shaped member having a sliding engagement within said slot, said platform arm extending outwardly axially of said one head, and a spring within said one head and engaging said platform arm so as to tend to maintain said platform in its normal position.

11. A work holder comprising a pair of opposed heads having compressible material on their opposed faces between which material segments may be inserted, shafts on which the heads are mounted, means for controlling the shafts comprising a sleeve surrounding each shaft and connected thereto so as to rotatably drive the shaft but allow for sliding movement of the shaft in the sleeve, step by step driving gearing con-

13

nected to the sleeves for rotating the same and the heads, a reciprocable means for each shaft and connected thereto to slide the same within the sleeves for moving the heads together or apart, and power means for moving said reciprocable means, said step by step driving gearing including a shaft, a pinion on each of said sleeves, other pinions engaging said first mentioned pinions and said shaft, and power means connected to said shaft whereby rotation of said shaft results in simultaneous rotation of said sleeves.

12. The work holder of claim 11 in which said last mentioned power means comprises a ratchet pinion mounted on said shaft, a pawl adapted to engage said ratchet pinion, and reciprocable means to which said pawl is fastened.

13. In combination a rotatable head for use in a work holder, a T-shaped member, a slot in said head, one arm of said T-shaped member being 15 slidable in said slot, a platform fixed to the other arm of said T-shaped member, said platform being located beyond an end of said head, the arm on which said platform is fixed extending

14

outwardly axially of said head, and a spring within said head engaging said platform arm and urging said platform arm to a position to one side of the axis of said head whereby said platform is located radially of said head rather than centrally thereof.
